UNITED STATES PATENT OFFICE.

SYLVESTER FRANCIS LESLIE, OF WEST MAITLAND, NEW SOUTH WALES, AUSTRALIA.

AUTOMATIC COUPLING.

1,072,626.

Specification of Letters Patent. Patented Sept. 9, 1913.

Application filed September 16, 1912. Serial No. 720,556.

To all whom it may concern:

Be it known that I, SYLVESTER FRANCIS LESLIE, a subject of the King of Great Britain and Ireland, residing at West Maitland, in the State of New South Wales, Commonwealth of Australia, have invented certain new and useful Improvements in Automatic Couplings, of which the following is a specification.

10 The present invention appertains to couplings for railroad vehicles and of the type adapted to engage automatically when the vehicles are brought together on the same track whereby the necessity is eliminated of 15 the operator or shunter passing between the vehicles to effect the coupling operation. And this invention has been devised to effect an improved automatic coupling for the purpose specified embodying with simplicity of construction positive action and adapted for uncoupling from the side of the vehicles. And according to this invention the improved automatic coupling for railroad rolling stock consists essentially of the combination with the ordinary form of a pair of U-shaped coupling links connected together by a union screw, of a peculiarly constructed link and operating mechanism operable to effect coupling by contact of 20 opposing buffers and adapted for disengagement by a lever positioned on each side of the adjacent vehicles as hereinafter particularly ascertained and specified in the appended claim.

35 Referring to the drawings appended to and forming part of this specification and wherein automatic coupling devices according to this invention are depicted:—Figure 1 is perspective view of ends of adjacent vehicles showing mechanism attached to one vehicle and in the “ready-to-couple” position. Fig. 1^a is a modified construction of buffer, and Fig. 2 is perspective view similar to Fig. 1 with coupling devices on 40 each of the coupled vehicles and showing the relative positions of the parts when the vehicles are coupled.

Referring particularly to Figs. 1 and 2 the casing 5 of each pair of spring buffers 6 of ordinary construction, has mounted thereon, or integral therewith as shown, a vertical apertured bracket 7 through each of which passes the rod member of a rod 8

whose outer or forward end carries a bracket 9 the bifurcated end 10 of which takes around 55 the shank of the buffer 6. A spring 11 for effecting the return movement of said rod 8 is provided intermediate of the outer face of said bracket 7 and the shank of the bracket 9. The inner or rearward end of 60 each of said rods 8 is pivotally connected to the bifurcated lower end 12 of a link 13 dependent from the transverse bar 14 secured in bearing brackets 15 positioned on the end 16 of the vehicle as shown. Said 65 transverse bar 14 has fixedly attached thereto an upwardly extending bracket 17 provided with an offset 18 and attached at its free end to one end of a spring 19 whose other end is attached to the extension 20 of 70 a detent catch 21 trunnioned in the ends of the pair of parallel horizontal members 22 of the bracket 23 affixed to the vehicle end 16. The catch 21 is adapted to effect engagement with the hooked free end 24 of an 75 arm 25 integral with or attached to one of the pair of parallel arms 26 fixedly secured to the transverse bar 27 rotatable in bearings underneath the buffer beams 28. To each of the ends of said transverse bar 27 80 is attached a handle 29. The parallel arms 26 are adapted when raised to support the pair of U-shaped coupling links 30 (connected by a union screw and attached to the vehicle draw-bar hook 31 in the ordinary manner as shown), the pair of pins or extensions 32 on each of said links 30 bearing on the upper faces of the arms 26 (see Fig. 1).

Referring now to Fig. 1^a in the modification shown the outer or forward end of the rod 8 is pivoted to a vertical bracket 9^a integral with the shank of the buffer 6 said bracket operating in a slot 6^a in the buffer casing 5 as shown, by which construction the 95 spring 11 and bracket 9 are eliminated.

In use, the coupling mechanism on one of the vehicle ends 16 being in the position shown in Fig. 1 when the vehicles are brought together the impact of opposing 100 buffers 6 forces the levers 8 toward their respective carrying vehicle ends 16 thereby effecting radial movement of the links 13, the consequent partial rotation of the transverse bar 14 forcing the free end of the 105 bracket 17 outward, which movement causes

the lower end of the catch 21 to move toward said bracket 17 and to disengage from the end 24 of the arm 25. The disengagement so effected depriving the arm 25 of support 5 permits it and the parallel arms 26 to fall when the outer of the U-shaped links 30 will effect engagement with the drawbar hook 31 of the opposing vehicle (see Fig. 2). The descent of the arms 26 causes partial rotation of their carrying bar 27 the terminal handles 29 taking up a horizontal or approximately horizontal position as shown in Fig. 2. To prevent any swinging motion of the arms 26 when in the dependent position 10 shown in Fig. 2 and during progress of the vehicles a suitable stop (not shown) is provided on each of the vehicles to limit the movement of the handles 29. The coupling mechanism at each end of a vehicle is arranged so that the arms 25 are not presented 15 in opposition to each other as also the catches 21. When the pressure of opposing buffers is released the operation of the spring 11 (or the buffer spring when the modification shown in Fig. 1^a is employed) causes the return to the normal position in Fig. 1 of the rods 8, links 13, transverse bar 14 and catch 21 whereby the latter is in position to again engage the end 24 of the arm 25 when the latter is raised by means of one 20 of the handles 29 (which movement will also raise the U-shaped links 30 out of engagement with the opposing drawbar hook 31).

25 To insure the correct positioning of the outer of the U-shaped coupling links 30 a

stop 32^a is provided on the upper surface of each of the arms 26.

What I claim and desire to secure by Letters Patent is:—

40 In the hereinbefore described coupling for railroad rolling stock comprising a coupling link secured to the end of one car and adapted to engage a hook on another car, a rock shaft journaled transversely to the end of 45 the vehicle and provided with handles, and a pair of parallel bars fixedly connected to said rock shaft, one of which has a hook-shaped extension, said bars engaging said coupling link to lower and raise it respectively into its coupling and uncoupling positions, in combination with a detent catch 50 reckably connected to the vehicle and engageable with said hook-shaped extension to uphold said bars and maintain said link in 55 its uncoupled position, a rock shaft, and an offset connected therewith, a spring attached to said detent catch and offset, an arm connected to each end of said second rock shaft, a spring-pressed rod pivotally connected to 60 the free end of each of said arms, and a buffer engageable with each spring-pressed rod to turn said second rock shaft and release the detent catch from said hook-shaped extension for the movement of said arms and 65 link to the coupling position.

Signed at Newcastle, N. S. W., Australia, this eighth day of July 1912.

SYLVESTER FRANCIS LESLIE.
